The ornamental design for a novelty wheel cover, as shown and described.

DESCRIPTION

FIG. 1 is a perspective view of a novelty wheel cover showing my new design therefor. The broken line drawing depicting a tire with lettered indicia is for purposes of demonstration of scale ratio only, and forms no part of my design. The broken line alpha-numeric indicia is for purposes of illustration only, and also forms no part of my design;

FIG. 2 is a front elevational view;

FIG. 3 is a rear elevational view;

FIG. 4 is a top plan view, the bottom plan view being a mirror-image thereof;

FIG. 5 is a left side elevational view; and,

FIG. 6 is a right side elevational view. The broken line drawings representing the upper and lower edges of a wheel are provided to illustrate depth of design features and form no part of my design.
